WIRE DRAWING MECHANISM

Edwin J. McIlvried, Akron, Ohio, assignor to The
Vaughn Machinery Company, Cuyahoga Falls,
Ohio, a corporation of Ohio

Application October 3, 1931, Serial No. 566,672

14 Claims. (Cl. 205—20)

For some time, in the wire drawing art, it has been recognized as desirable to cool the wire, and more especially certain kinds of wire, at or following its passage through the die, and with this object in view to provide means for cooling both the wire drawing drum or block and the wire that is being wound thereon, whether such wire be simply passed around the block a plurality of times at an intermediate point in a continuous wire drawing bench or be wound up into a coil on the terminal block of such a bench or on an individual type of block.

The object of the present invention is to provide a simple and compact arrangement of fan and ducts whereby a current of air may be passed over a drawing block, whether one in a series on a bench or operated individually. A further object is to subdivide such current of air and direct the individual streams in the most effective cooling relation to the wire that is being wound upon the block.

To the accomplishment of the foregoing and related ends, the invention, then, consists of the means hereinafter fully described and particularly pointed out in the claims, the annexed drawings and the following description setting forth in detail certain mechanism embodying the invention, such disclosed means constituting, however, but one of various mechanical forms in which 30 the principle of the invention may be used.

In said annexed drawings:—

Fig. 1 is partly a side elevation and partly a vertical section through a wire drawing mechanism including the present improved cooling means; Fig. 2 is a vertical section taken on a plane at right angles to that of Fig. 1, as indicated by the line 2—2 thereon; and Fig. 3 is a broken horizontal section with parts appearing in elevation, the plane of the section being in general indicated by the line 3—3, Fig. 1, it being noted that the plane of the sectioned parts appearing in Fig. 1 is indicated by the line 1—1 on said Fig. 3.

For the purpose of illustrating the present improved construction of cooling means, such means are shown in connection with a wire drawing mechanism of the individually driven type such as will be found disclosed in U. S. Patent No. 1,723,313, issued to P. V. Tippet under date of 45 August 6, 1929. It will be understood, however, that such cooling means are not limited in their application to any such particular type of block but may be advantageously incorporated in benches comprising a plurality of blocks, particularly where the latter are driven by separate motors.

The main frame 1 of the single block wire drawing mechanism illustrated in the drawings is a rectangular box-like structure, preferably formed 55 of an integral casting, the side walls of which are

connected at an intermediate point by a transverse partition 2 above which is located the driving mechanism for the block, as will be presently described. The upper portion of such frame is partially closed off by an annular plate 3 that forms a top for the machine, and located a short distance therebelow is a correspondingly annular web or partition 4, the inner edge of which is joined with the corresponding edge of said top 3 by a vertical wall 5 so as to form a chamber 6 of 70 the general extent and substantially annular shape clearly indicated in Fig. 3.

The drum or block 7, which is in general of standard construction, is mounted on the upper end of a vertical spindle 8, the lower end of which 75 is journaled in a bearing 9 provided in a supplemental frame 10 of general cylindrical form. Such frame is removably supported, by means of an integral flange 11 about its upper edge, in the circular opening defined by the wall 5, such 80 flange resting on the annular top 3, as shown in Fig. 2, and being bolted or otherwise removably secured to such top. A plate 12, preferably of conical form, is fitted to the upper end of supplemental frame 10, having a flange 12 that rests 85 upon and interlocks with the flange 11 of said frame, and is secured along with the latter to the top 3. A bearing 13 is provided in said plate wherein the upper end of the shaft 2 is journaled just below the block 7. 90

Attached directly to one side of the main frame 1 is a second shell-like supplemental frame 15 which forms the mounting for the motor 16, whereby the vertical spindle 8 that supports the block 7 is driven. At the same time said supplemental frame forms a housing for a blower fan, as will be explained. The driving connections comprise a worm 17 on the inner end of a shaft 18 that constitutes in effect a continuation of the motor spindle 19, such shaft being journaled in 95 a bearing 20 therefore provide in the adjacent side wall of main frame 1. As a matter of fact, in the construction shown, this bearing is formed in a boss or hub 15a on the adjacent face of supplemental frame 15, such boss projecting through 100 an opening in the side wall of the main frame 1. The worm 17 meshes in turn with a worm gear 21 keyed on the lower end of the spindle 8, supplemental frame 10 being cut away at 10a to provide clearance. 110

The motor will desirably be enclosed, as shown in Fig. 1, in a guard 22, the top 23 of which lies on a level with the top 3 of the main frame, and jointly supported upon guard top 23 and main frame top 3 is a vertical shield 24 that more or 115 less completely encloses the mechanism on top of the main frame.

The web 4 that forms the floor of the chamber 6 in the main frame is depressed at one corner of the latter to form an inlet connection 25 which 120

freely communicates with the interior of the shell 15 that forms the supplemental frame on which the motor is mounted, as just described above. This shell, in addition to thus supporting the motor, forms a housing for a centrifugal blower 26 that is mounted on the motor spindle 17 and serves when the motor is running to draw a current of air into the shell and discharge the same through passage 25 into chamber 6. From the latter the air is permitted to escape through a plurality of openings 27 circularly disposed in the top 3 of the main frame, and thence through aligned openings 28 into the interior of an annular shield 29 that surrounds the lower end of block 7. Such end, it will be noted (see Fig. 2), is in the form of an outwardly directed flange 7a, just above which the cylindrical wall of the drum is provided with a series of radial apertures 7b. The shield 29 rises to a level somewhat above such flange 7a and is itself provided with a rebent lip or downwardly directed flange 30 that has a close working fit with the edge of flange 7a and is provided with a series of apertures 31 located adjacent the upper surface of flange 7a. The rebent lip 30 serves as a means for preventing the coils of wire, when they become loosened, from dropping down and getting caught between the drum flange 7a and the shield 29.

The operation of the machine may now be described, giving special attention to the means provided for cooling the drum or block 7 and the coil of wire being wound thereon. The current of air supplied by the blower 26 to the chamber 6 will build up in the latter a substantial pressure which will be in turn conveyed into the annular space within the shield 29. From the latter in turn the air is permitted to escape both into the lower part of the drum or block and thence through the openings 7b formed in the side wall of the latter, and directly through the openings 31 formed in the downturned flange 30 on the shield itself. It will thus be seen that cooling currents of air are discharged both through and against the vertical wall of the drum or block. Accordingly, not only is such drum or block effectively cooled, but the wire as it is wound upon such block, whether in a relatively few number of turns for an intermediate pass or in a larger coil in a final stage of the drawing operation, will likewise be cooled by the passage of air therethrough from the interior of the block and the currents of air striking against its exterior.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In wire drawing mechanism, the combination of a frame including a substantially annular chamber connected with a fluid-pressure supply, a spindle disposed centrally of such chamber, a drum carried by the end of said spindle with its base contiguous to such chamber, and a hollow shield on said frame surrounding the base of said drum and having a series of apertures in proximity to such base said apertures opening in the direction substantially normal to the surface of said drum, the interior of said shield being in communication with the chamber in said frame.

2. In wire drawing mechanism, the combination of a frame including a substantially annular chamber connected with a fluid-pressure supply,

a spindle disposed centrally of such chamber, a drum carried by the end of said spindle and having a flanged base contiguous to such chamber, a hollow shield on said frame extending around, and having a rebent lip abutting, the flange on said drum, such lip and the wall of said drum each having a series of apertures in proximity to such flange and the interior of said shield being in communication with the chamber in said frame.

3. In wire drawing mechanism, the combination of a frame including a substantially annular chamber, a spindle disposed centrally of such chamber, a drum carried by the end of said spindle with its base contiguous to such chamber, and a hollow shield on said frame surrounding the base of said drum and having a series of apertures in proximity to such base, the interior of said shield being in communication with the chamber in said frame, a motor attached to one side of said frame and connected to drive said spindle, and a blower also driven by said motor and connected to supply fluid under pressure to such chamber, and through said apertures against the surface of said drum.

4. In wire drawing mechanism, the combination of a frame, a spindle mounted in said frame, a drum carried by one end of said spindle, a motor attached to said frame and connected to drive said spindle, a blower also driven by said motor, and means adapted to conduct fluid under pressure through said motor and by means of said blower to points adjacent to said drum.

5. In wire drawing mechanism, the combination of a frame, a spindle mounted in said frame, a drum carried by one end of said spindle, a motor attached to said frame and connected to drive said spindle, a blower also driven by said motor, and means adapted to conduct fluid under pressure through said motor and by means of said blower to the interior of said drum, the wall of the latter being apertured to permit escape of such fluid.

6. In wire drawing mechanism, the combination of a frame, a spindle mounted in said frame, a drum carried by one end of said spindle, a motor attached to said frame and having a spindle connected to drive said drum spindle, a blower fan carried by said motor spindle, and means adapted to conduct fluid under pressure through said motor and by means of said blower fan to the interior of said drum, the wall of the latter being apertured to permit escape of such fluid, said means being also adapted to discharge a portion of such fluid at points exterior to said drum but adjacent the wall thereof.

7. In wire drawing mechanism, the combination of a frame, a spindle mounted in said frame, a drum carried by one end of said spindle, a motor attached to said frame and having a spindle connected to drive said drum-spindle, a blower fan carried by said motor spindle, and means adapted to conduct fluid under pressure through said motor and by means of said blower fan to the interior of said drum, the wall of the latter being apertured to permit escape of such fluid, said means being also adapted to discharge a portion of such fluid at points exterior to said drum but adjacent the wall thereof.

8. In wire drawing mechanism, the combination of a frame, a spindle mounted in said frame, a drum carried by one end of said spindle, a removable supplemental frame, an annular flange on said supplemental frame adapted to make a precise fit with a complementary shoulder on

said first-named frame in the form of a housing attached to said first named frame, a motor attached to said housing having a spindle extending therethrough and connected to drive said 5 drum-spindle, a blower fan located in said housing carried by said motor spindle, and means adapted to conduct fluid under pressure from said housing to the interior of said drum, the wall of the latter being apertured to permit escape 10 of such fluid, said means being also adapted to discharge a portion of such fluid at points exterior to said drum but adjacent the wall thereof.

9. In wire drawing mechanism, the combination 15 of a drum having an outwardly and radially projecting flange, a hollow shield extending around the outer periphery of such flange and having a series of external apertures in proximity and disposed at approximately right angles to 20 the outer surface of said drum, and means for supplying a cooling fluid under pressure to the interior of said shield.

10. In wire drawing mechanism, the combination 25 of a drum having an outwardly projecting flange, the wall of said drum having a series of apertures in its wall adjacent such flange, a hollow shield extending around the outer periphery of such flange and having a series of external apertures in proximity and disposed at approximately 30 right angles to the outer surface of said drum, and means for supplying a cooling fluid under pressure to the interior of said shield and through said apertures to the exterior surface of said drum.

35 11. In wire drawing mechanism, the combination of a drum having an outwardly projecting flange, a hollow shield extending around the outer periphery of and having a rebent lip abutting such flange, such lip and the wall of said 40 drum each having a series of apertures in proximity and disposed substantially parallel to the flange on said drum, and means for supplying a

cooling fluid under pressure to the interior of said shield and through said apertures to the exterior surface of said drum.

12. In wire drawing mechanism, the combination 80 of a frame including a chamber connected with a fluid-pressure supply, a drum mounted on said frame with its base contiguous to such chamber, and a hollow shield on said frame exteriorly surrounding the base of said drum and having a series of apertures in proximity to such base, said apertures opening in a direction substantially normally and opposed to the exterior surface of said drum, the interior of said shield being in communication with the chamber in 85 said frame.

13. In wire drawing mechanism, the combination 90 of a frame including a chamber connected with a fluid-pressure supply, a drum mounted on said frame with its base contiguous to such chamber, and a hollow shield on said frame exteriorly surrounding the base of said drum and having a series of apertures in proximity to such base, said apertures opening in a direction substantially normal and opposed to the exterior surface of said drum, the interior of said shield being in communication with the chamber in 95 said frame at a plurality of spaced points.

14. In wire drawing mechanism, the combination 100 of a frame including a chamber connected with a fluid-pressure supply, a drum mounted on said frame with its base contiguous to such chamber, and a hollow shield on said frame exteriorly surrounding the base of said drum and having a series of apertures in proximity to such base, said apertures opening in a direction substantially 105 normal and opposed to the exterior surface of said drum, the interior of said shield being in communication with the chamber in said frame, the wall of said drum also having a series of apertures and the interior of said drum being in 110 communication with the interior of said shield.
